UNITED STATES PATENT OFFICE.

ROBERT D. LOOSE, OF FORT WORTH, TEXAS.

ATTACHMENT FOR CARBURETERS.

1,181,782.

Specification of Letters Patent.

Patented May 2, 1916.

Application filed June 28, 1915. Serial No. 36,756.

To all whom it may concern:

Be it known that I, ROBERT D. LOOSE, a citizen of the United States, and a resident of the city of Fort Worth, in the county of Tarrant and State of Texas, have invented a certain new and useful Improvement in Attachments for Carbureters; and I do hereby declare that the following description of said invention, taken in connection with the accompanying sheet of drawings, forms a full, clear, and exact specification, which will enable others skilled in the art to which it appertains to make and use the same.

15 My invention relates generally to improvements in attachment for carbureters, and it consists, essentially, in the novel and peculiar combination of parts and details of construction, as hereinafter first fully set forth and described and then pointed out in the claims.

The essence of my invention resides in providing the outlet portion of a carbureter for a hydro-carbon engine with means, 25 whereby there is induced a vertical whirl to the volatilized gases passing from said carbureter. And correlated therewith are other means whereby the passage of said gases through the outlet portion of said carbureter, may be estopped entirely, or reduced in volume to any desired degree.

Briefly speaking, the outlet portion of my carbureter is possessed of a plurality of helical vanes on the interior thereof imparting 35 the vertical whirl or movement to the volatilized mixture passing therethrough. And located between adjacent vanes are provided means whereby the mixture may be entirely estopped from passing through the helical 40 channels produced by said vanes; or said means may be so adjusted as to attenuate the flow of the mixture through the channels between the adjacent helical vanes as hereinafter described.

45 In the drawing already referred to, which serves to illustrate my said invention more fully, Figure 1 is a plan section of my device, the same being taken in line 1—1 of Fig. 2 and showing the means for closing the 50 channels between the helical vanes in closed position. Fig. 2 is a longitudinal vertical section of a separate shell in which my invention is embodied, the said section being taken in line 2—2 of Fig. 1, and likewise 55 designating said channels as being closed

by said closing means. Fig. 3 is a plan section similar to that of Fig. 1, but showing the channel closing media in a partially open position to permit an attenuated flow of volatilized mixture therethrough. Fig. 4 60 is a vertical section in line 4—4 of Fig. 3. Fig. 5 is an elevation of the upper portion of a typical carbureter, within which is incorporated my invention.

Like parts are indicated by corresponding 65 symbols or characters of reference in all the figures of the drawing.

It is well known that in the volatilization of a liquid hydro-carbon as takes place in the carbureter of an engine of the class described, there are a plurality of hydro-carbon molecules which pass through the carbureter in a liquid state, and it is to the end of breaking up these molecules and insuring 70 a more thorough mixture that my device is 75 produced.

Referring now to the drawing. A designates the upper portion of the shell of a carbureter, as seen in Figs. 4 and 5, while A', Fig. 2, indicates a separate shell adapted to 80 be introduced between a typical type of carbureter and the intake manifold of a motor, so that my invention may be installed in 85 power plants now in operation.

In the case of my device being incorporated as a part of a carbureter, B is the flange thereof adapted to mate or match with a like flange (not shown) upon the lower end of an intake pipe of a motor of the character specified, the bolt holes C being provided whereby the carbureter may be fixed in position to said flange of said intake pipe. On the other hand, if my device be constituted as a separate structure, then there is formed on the lower end of the shell A', 90 Fig. 2, a flange 50. In this instance, this flange 50 will connect with a like flange (not shown) on the carbureter, and the flange B will connect with the intake manifold as already described. In either structure the essentials of my invention are precisely the 95 same.

The shell A is annular in plan, as seen in the drawing and the usual butterfly or other throttle valve is dispensed with. Instead, however, there are provided or integrally formed within said shell a plurality of vertical helical vanes 10, spaced equidistantly apart within the shell A, the inner edges of said vanes abutting, or formed integral 100

110

with an axial upstanding post 11, which is of preferably square cross section as will hereinafter more fully appear. And it is now to be stated that the upper edges of the 5 vanes 10 are preferably faced in a vertical plane so that the same present in plan a single line 12 as seen in Figs. 1 and 3. Pivoted for oscillation in the interior of the said shell A preferably at the upper 10 ends of the vanes 10 are a plurality of diaphragms 13, the same having their outer contours 14 fitting the inner contour of the shell A and their inner contours abutting the respective faces of the upstanding post 11. These diaphragms are substantially triangular in shape with the base and altitudinal edges 15 and 15^a, as it were, abutting against the upper perpendicular edge of one of the vanes 10, and the other edge 15^a 15 being beveled off upon its under side, to lie upon the upper edge of the next succeeding vane 10, as seen in Figs. 1 and 2, so that the said diaphragms and upper edges present a plane surface when the diaphragms are in 20 horizontal or closed position to estop the passage of volatile matter through the channels formed by the vanes 10.

Medially of the arcuate length of the outer edges 14 of the diaphragms 13 are 25 produced bosses or protuberances 16 which are internally apertured for the reception of studs 17. These studs 17 are pinned fast to said diaphragms and extend radially through the shell A as clearly seen 30 in the drawing, and, on the exterior of said shell, are possessed of depending levers 18, which are likewise pinned or otherwise fixed to said studs. The said levers have their lower ends 19 arcuate, said arcs having 35 their centers coincident with the axes of the studs 17; and, on the peripheries of said arcuate ends 19 are cut or otherwise formed, spur or gear teeth 20, coacting with like teeth 21 produced at intervals in the 40 upper edge of an annular band 22 embracing the exterior of the shell A and partially rotatable therearound. This band is preferably made in two halves and joined together by screws 23 passing 45 through ears 24 on the halves to facilitate placing said band in position while assembling the parts. To maintain this band in proper position on said shell there is formed a shoulder 25 around the 50 shell A upon which the band rests in an obvious manner. And, it being understood that the plurality of levers 18 having their teeth 20 in mesh with the teeth 21 of the band 22 up or down movement of said band 55 is prevented. Attention is now directed to the fact that the number of teeth on each lever corresponds with the number of teeth on the band with which that particular lever coacts, and the number of such teeth 60 is so arranged that when the last tooth of

each of the levers engages the last tooth of each set on the band through the partial rotation of the said band, the diaphragms 13 will have been rotated from a fully closed to a fully open position to permit the full 70 flow of the gases through the channels formed by the vanes 10. Further rotation of the diaphragms is prevented by the engagement of studs 26 on the band 22 against the arcuate ends 19 of the levers 75 18 in a manner readily understood. Projecting from the band 22 is a handle member 27, having a forked end 28 or like member for attachment of rods or links whereby the band may be actuated from a 80 distance, as for instance from the seat of an automobile.

The functioning of my device as thus far disclosed may now be described as follows, it being understood that the position of the 85 levers 18 as seen in Fig. 5 indicates the closed position of the diaphragms 13, in which position no gas may pass out of the carbureter to the motor. But upon movement of the handle 27 to the position shown 90 in Fig. 3, it will be observed that each of the diaphragms have been slightly tilted, the edges 15^a thereof arising from their coacting ends of the respective vanes 10, and the opposite edges 15 descending below 95 the next adjacent vane, as clearly seen in Figs. 3 and 4, thereby producing two openings 29 and 30, Fig. 3, for each channel. The upflowing gas passes through the said channels in a vertical whirl and strikes the 100 diaphragms, is deflected thereby and then passes through the said openings 29 and 30. As the gas strikes the diaphragms the liquid molecules are broken up as it were, and by reason of the vertical action are 105 kneaded and intermingled, and caused to become a part of the volatilized mixture, thereby producing a far more homogeneous mass than is possible at the present time. And I have proved by extended experiments that by employing the combination 110 of the helical vanes and the diaphragms, which also act as baffle plates, the mixture is capable of absorbing or taking up much more oxygen than before, and that a slight 115 opening of the diaphragms produces practically the same result as a full opening of the usual butterfly type of throttle valve.

In order to supply the required amount of extra oxygen as above stated, I pierce 120 the walls of the shell A, directly below the lower ends of the vanes with a plurality of openings 31 corresponding in number to the number of vanes. Embracing the exterior of the shell A and adapted to close 125 these openings, is provided an annular split or halved band 32, joined together by screws 33 and ears 34 and it is to be noted that said band rests upon a shoulder 35, surrounding the shell A, to maintain the same at proper 130

elevation. The band 32 has openings 36 therethrough corresponding in size and number with the openings 31 in the shell A, so that by rotating said band the openings 31 and 36 may be brought in or out of register as the case may be. Pivoted to the band 22 is a depending link 37 having a long slot 38. The lower end of this link also has a slot 38a adapted for the passage 10 therethrough of a pin 39 fastened to the band 32. Passing through the slot 38 is a headed screw 40 threaded into any one of the threaded apertures 41 in the shell A. This screw 40 acts as a fulcrum for the link 37, so that as the band 22 is rotated the band 32 is likewise turned to either open or close the oxygen openings 31 in the shell. And it will be easily understood that the extent of the rotation of the band 32 with 20 respect to the band 22 may be varied by entering the fulcrum screw 40 into any one of the openings 41 and thereby changing the relative rotation of the bands and varying the extent of uncovering the oxygen openings 31. In this manner the driver of a car 25 may properly regulate the amount of extra oxygen admitted in a manner that is simplicity itself.

While herein I have described, and disclosed the preferred embodiment of my invention, I may make various alterations and changes therein, all of which changes are to be considered within the scope of my invention under a broad interpretation of the doctrine of equivalents. For instance I may place the closing diaphragms at the lower 35 end of the vanes or within the channels at any point intermediate the length thereof as may be desired.

40 It is now to be understood that this invention may be embodied in any carbureter now on the market by slightly lengthening the upper portion A of such device and slightly changing the shape thereof to that 45 shown in the drawing. My invention may also be applied as a separate entity by providing the same with a flange 50 at its lower end, as seen in Fig. 2, so that the device may be bolted between a carbureter and the 50 intake flange of a motor. This construction will enable the owner of a typical carbureter to remove the throttle valve therefrom, and apply my invention in a manner easily understood.

55 I have hereinbefore disclosed the preferred mode of practising my invention, but I reserve the right to make such and any changes as might occur to one skilled in the art to which this invention appertains, or to 60 make any and all such alterations as may be permitted under the doctrine of equivalents.

I claim—

1. An article of the class described including a hollow shell having an inlet and 65 outlet, helical vanes arranged on the inte-

rior of said shell and having helical passages between said vanes, and means simultaneously closing said passages.

2. An article of the class described including a hollow shell having an inlet and 70 outlet, helical vanes arranged on the interior of said shell and having helical passages between said vanes, externally actuated diaphragms in said passages adapted to regulate the opening through said 75 passages.

3. An article of the class described including a hollow shell having an inlet and outlet, of internal means for imparting a 80 vertical whirl to gases passing through said shell, and oscillating diaphragms in said shell adapted to coact with said first named means regulating the passage through said shell of said gases.

4. An article of the class described including a hollow shell having an inlet and outlet, of internal means for imparting a 85 vertical whirl to gases passing through said shell, and externally and simultaneously actuated oscillating diaphragms in said shell 90 adapted to coact with said first named means regulating the passage through said shell of said gases.

5. An article of the class described including a hollow shell having an inlet and 95 outlet, helical vanes on the interior of said shell and helical passages between said vanes, diaphragms within said shell closing said passages, and oscillatable means on the exterior of said shell connected to 100 said diaphragms.

6. An article of the class described including a hollow shell having an inlet and outlet, helical vanes on the interior of said shell and helical passages between said 105 vanes, diaphragms within said shell closing said passages, and oscillatable means on the exterior of said shell connected to said diaphragms, there being openings through the walls of said shell, an annular oscillatable band on said shell adapted to cover said openings, and means connecting said oscillatable means and said band to actuate said band.

7. The combination of a hollow open ended shell and openings in the wall thereof, means within said shell imparting a vertical whirl to gases passing therethrough, coacting means estopping the passage of 115 said gases through said shell, and means co-operating with said coacting means closing the openings in the wall of said shell.

8. The combination of a hollow open ended shell and openings in the wall thereof, means within said shell imparting a vertical whirl to gases passing therethrough, coacting means regulating and estopping the 125 passage of said gases through said shell, and means co-operating with said coacting means regulating and closing the openings in the 130

wall of said shell, whereby the closing of said openings is effected simultaneously with estoppel of the passage of said gases.

9. The combination of a hollow open ended shell and openings in the wall thereof, means within said shell imparting a vortical whirl to gases passing therethrough, coacting means estopping the passage of said gases through said shell, external devices on said shell actuating said estopping means, and means coöperating with said coacting means closing the openings in the wall of said shell.

10. The combination of a hollow open ended shell, of a plurality of vanes within said shell, there being channels between said vanes for the passage therethrough of gases, and adjustable closures for said channels.

11. The combination of a hollow open ended shell, of an axial postextending therethrough, there being a plurality of equally spaced vanes within said shell with their inner edges contacting said post, and movable closures for the spaces between said vanes.

12. The combination of a hollow open ended shell, of an axial postextending there-

through, there being a plurality of equally spaced vanes within said shell with their inner edges contacting said post, and simultaneously actuated movable closures for the spaces between said vanes.

13. The combination of a hollow open ended shell, a plurality of helical vanes extending therethrough and an axially extending post, producing a plurality of helical channels through said shell, oscillatable diaphragms adapted to close said channels, and external means embracing said shell, simultaneously actuating said diaphragms.

14. The combination of a hollow open ended shell, a plurality of helical vanes extending therethrough and an axially extending post, producing a plurality of helical channels through said shell, oscillatable diaphragms adapted to close said channels, and external means embracing said shell, simultaneously actuating said diaphragms, there being openings through the wall of said shell, and a band connected with said actuating means to close said openings.

In testimony that I claim the foregoing as my invention, I have hereunto set my hand.

ROBERT D. LOOSE.
